FIG. 4 is a back view of the container with surface indicia of FIG. 1;

FIG. 5 is a second side view of the container with surface indicia of FIG. 1;

FIG. 6 is a top view of the container with surface indicia of FIG. 1; and

FIG. 7 is a bottom view of the container with surface indicia of FIG. 1;

FIG. 8 is a front perspective view of a container with surface indicia, embodying an embodiment of our new design;

FIG. 9 is a front view of the container with surface indicia of FIG. 8;

FIG. 10 is a first side view of the container with surface indicia of FIG. 8;

FIG. 11 is a back view of the container with surface indicia of FIG. 8;

FIG. 12 is a second side view of the container with surface indicia of FIG. 8;

FIG. 13 is a top view of the container with surface indicia of FIG. 8; and

FIG. 14 is a bottom view of the container with surface indicia of FIG. 8;

FIG. 15 is a front perspective view of a container with surface indicia, embodying an embodiment of our new design;

FIG. 16 is a front view of the container with surface indicia of FIG. 15;

FIG. 17 is a first side view of the container with surface indicia of FIG. 15;

FIG. 18 is a back view of the container with surface indicia of FIG. 15;

FIG. 19 is a second side view of the container with surface indicia of FIG. 15;

FIG. 20 is a top view of the container with surface indicia of FIG. 15; and

FIG. 21 is a bottom view of the container with surface indicia of FIG. 15;

FIG. 22 is a front perspective view of a container with surface indicia, embodying an embodiment of our new design;

FIG. 23 is a front view of the container with surface indicia of FIG. 22;

FIG. 24 is a first side view of the container with surface indicia of FIG. 22;

FIG. 25 is a back view of the container with surface indicia of FIG. 22;

FIG. 26 is a second side view of the container with surface indicia of FIG. 22;

FIG. 27 is a top view of the container with surface indicia of FIG. 22; and

FIG. 28 is a bottom view of the container with surface indicia of FIG. 22;

FIG. 29 is a front perspective view of a container with surface indicia, embodying an embodiment of our new design;

FIG. 30 is a front view of the container with surface indicia of FIG. 29;

FIG. 31 is a first side view of the container with surface indicia of FIG. 29;

FIG. 32 is a back view of the container with surface indicia of FIG. 29;

FIG. 33 is a second side view of the container with surface indicia of FIG. 29;

FIG. 34 is a top view of the container with surface indicia of FIG. 29; and

FIG. 35 is a bottom view of the container with surface indicia of FIG. 29;

FIG. 36 is a front perspective view of a container with surface indicia, embodying an embodiment of our new design;

FIG. 37 is a front view of the container with surface indicia of FIG. 36;

FIG. 38 is a first side view of the container with surface indicia of FIG. 36;

FIG. 39 is a back view of the container with surface indicia of FIG. 36;
FIG. 40 is a second side view of the container with surface indicia of FIG. 36;
FIG. 41 is a top view of the container with surface indicia of FIG. 36; and
FIG. 42 is a bottom view of the container with surface indicia of FIG. 36;
FIG. 43 is a front perspective view of a container with surface indicia, embodying an embodiment of our new design;
FIG. 44 is a front view of the container with surface indicia of FIG. 43;
FIG. 45 is a first side view of the container with surface indicia of FIG. 43;
FIG. 46 is a back view of the container with surface indicia of FIG. 43;
FIG. 47 is a second side view of the container with surface indicia of FIG. 43;
FIG. 48 is a top view of the container with surface indicia of FIG. 43; and
FIG. 49 is a bottom view of the container with surface indicia of FIG. 43;
FIG. 50 is a front perspective view of a container with surface indicia, embodying an embodiment of our new design;
FIG. 51 is a front view of the container with surface indicia of FIG. 50;
